W. S. BACHMAN

STERILIZING ATTACHMENT FOR WATER SUPPLY PIPES

Filed March 20, 1922

Fig. 1.

FIG. 2.

FIG. 3.

Inventor
Walter S. Bachman
by Clarke C. Melville Atty.

UNITED STATES PATENT OFFICE.

WALTER S. BACHMAN, OF CHICAGO, ILLINOIS.

STERILIZING ATTACHMENT FOR WATER-SUPPLY PIPES.

Application filed March 20, 1922. Serial No. 544,982.

To all whom it may concern:

Be it known that I, WALTER S. BACHMAN, a citizen of the United States, and a resident of Chicago, in the county of Cook and State 5 of Illinois, have invented certain new and useful Improvements in Sterilizing Attachments for Water-Supply Pipes; and I do hereby declare that the following is a full, clear, and exact description thereof, 10 reference being had to the accompanying drawings, and to the letters of reference thereon, which form a part of this specification.

This invention relates to improvements in 15 sterilizing attachments for water supply pipes and consists of the matters hereinafter described and more particularly pointed out in the appended claims.

The object of the invention is to provide a 20 simple and efficient water sterilizing device, which may be quickly and easily interposed in any water supply pipe line, and which will operate automatically to discharge a small quantity of sterilizing agent into the 25 water flowing through said pipe.

Another object of the invention is to provide a device which is cheap and economical to manufacture and which may be readily charged with the sterilizing agent when first 30 installed and also may be recharged when the sterilizing efficiency of the agent has been exhausted.

These and other advantages of the novel 35 sterilizing attachment will appear more fully as I proceed with my specification.

In the drawings:—

Figure 1 is a view representing a side elevation of a sterilizing attachment embodying the invention, interposed in a water pipe 40 line connected to a drinking water filter;

Figure 2 is a view representing, on an enlarged scale, a vertical central section through the sterilizing attachment;

Figure 3 is a view representing, on still 45 further enlarged scale, a transverse section through a pipe contained in the sterilizing attachment, in a plane indicated by the line 3—3 of Fig. 2.

Referring now to that embodiment of the 50 invention illustrated in the drawings:—5 indicates a water supply pipe line and 6 indicates the improved sterilizing attachment. As shown in the drawings, the pipe 5 supplies water to a filter 7, but as will be apparent, the invention is not limited to use 55 in connection with a drinking water filter,

and may be used in other places when its characteristic operation makes its use advantageous. The filter has a discharge pipe 5^a, with a faucet 8 to control the flow from the 60 filter.

The sterilizing attachment consists of a vertically elongated tubular casing or shell 9, adapted to contain a charge of the sterilizing agent and of a pipe 10 extending 65 through the interior of said casing,—the pipe 10 being provided with one or more screened openings 11 through which a small amount of the sterilizing agent is admitted 70 to the water which passes through said pipe.

The casing 9 is made of non-corrosive metal and is of such diameter and height as compared to the diameter of the pipe 10, that it will contain a sufficient charge of 75 the sterilizing agent to last for a considerable length of time, without the necessity of recharging. The pipe 10 as shown is the same diameter as that of the pipe 5, to which the sterilizer is attached.

The casing 9 is open at the top. 12 indicates a flat disc having an aperture 13 in which the pipe 10 is fixed in any suitable or well-known manner. The disc 12 provides a closure for the top of the casing 9 and is removably secured thereto by any 80 convenient means. As shown, this means consists of swing bolts 14 pivoted to ears 15 on the casing adapted to engage in notched, 85 projecting lugs 16 on the disc 12, so that fly nuts 17 on said bolts will act to draw the 90 disc tightly against the top of the casing,—a gasket 18 being interposed to make the closure water-tight.

The casing 9 has a reduced, internally-threaded end 19 into which the pipe is 95 threaded. A nut and washer 20 locks the pipe against turning movement and makes a water-tight connection at this point.

The pipe 10 is provided with one or more 100 holes or openings 11 to permit a small inflow of the sterilizing fluid from the casing 9 to the water in the pipe 10. As shown, these openings are each protected by a screen 11^a made preferably of filter stone or other composition which will permit of a small 105 flow of liquid. Said screen is secured in a metal thimble 11^b which is threaded into the opening in the pipe 10.

The pipe 10 is connected at the top, above 110 the casing 9, by a fitting 21 to the pipe 5, and at the bottom, below the casing 9, by a fitting 22 to a pipe 5^b connected to the filter

7. A shut-off valve 23 above the fitting 21, permits the water supply to be cut off when the sterilizing attachment is being installed in the first instance and when it is being 5 later recharged. The casing is provided with an inlet opening 24, closed by a removable, threaded plug 25, for filling it with the sterilizing agent.

The operation of the attachment is as follows:—The casing 9 is charged with the sterilizing agent in liquid form by filling it through the opening 24. The attachment is then connected in position as hereinbefore described. The sterilizing fluid, after a 15 balance of pressure is attained between the fluid in the casing 9 and the water in the pipe 10 (by reason of the connection between the two through the porous openings of the screens 11^a) appears to fill the porous 20 screens 11^a.

The sterilizing agent preferably used is a weak chlorine gas solution. Upon the flow of water through the pipe 10, as when the faucet 8 is turned on, a minimum amount of 25 the sterilizing element is drawn through the porous screen or screens 11^a (whether by aspiration or otherwise is not thoroughly understood) and is absorbed by the water flowing through said pipe, to an extent sufficient to thoroughly sterilize the water. The 30 number and size of the screened openings depend upon the cross-sectional area of the pipe 10 and of the normal intended rate of flow of water therethrough and may be determined by experiment.

The thimbles 11^b carrying the screens of filter stone, being removable, may be removed and replaced when the porous screens become filled so as to obstruct the required 40 limited flow of the sterilizing agent into the pipe 10.

While in describing the invention I have referred to the several details of mechanical construction and arrangement as illustrated 45 in the drawings, it is to be understood that the invention is not limited thereto, except as may be pointed out in the appended claims.

I claim as my invention:—

50 1. A sterilizing attachment adapted to be interposed in a water supply line, comprising a casing closed at both ends and adapted to contain a sterilizing agent, a pipe extend-

ing through said casing and through the closed ends thereof, which casing provides a closed chamber surrounding a part of said pipe, that part of said pipe between the closed ends of said casing having one or more holes therein, and a screen of porous material closing each of said holes. 55 60

2. A sterilizing attachment adapted to be interposed in a water supply line, comprising a casing containing a sterilizing agent, a pipe extending therethrough, means for closing the ends of said casing upon said pipe to provide a closed chamber surrounding said pipe, said pipe being provided with one or more holes in its length within said chamber, a thimble threaded in said hole, and a screen of porous material fixed in said 70 thimble. 75

3. A sterilizing attachment adapted to be interposed in a water supply line, comprising an elongated casing open at the top, a removable closure attached water tight to the top of said casing, a pipe extending through and fixed in said closure, said pipe extending through said casing, means providing a water-tight, removable joint connecting said pipe to the bottom of said casing, said pipe being provided with one or more holes in its length within said casing, and a porous screen closing each of said 80 holes. 85

4. A sterilizing attachment adapted to be interposed in a water supply line, comprising an elongated casing open at the top, a removable closure attached water-tight to the top of said casing, a pipe extending through and fixed in said closure, said pipe extending through said casing, means providing a water-tight, removable joint connecting said pipe to the bottom of said casing, said pipe being provided with one or more holes in its length within said casing, a removable thimble fixed in each of said 90 holes, and a screen of filter stone fixed in each thimble. 95

In testimony that I claim the following as my invention, I affix my signature in the presence of two witnesses, this 17th day of March, A. D. 1922.

WALTER S. BACHMAN.
